UNITED STATES PATENT OFFICE

CECIL S. KELLEY, OF EAST MCKEESPORT, PENNSYLVANIA, ASSIGNOR TO THE WESTINGHOUSE AIR BRAKE COMPANY, OF WILMERDING, PENNSYLVANIA, A CORPORATION OF PENNSYLVANIA

SIGNAL HORN

Application filed February 5, 1930. Serial No. 426,077.

This invention relates to sound producers, and more particularly to a sound producer of the type employing a flexible diaphragm which is caused to vibrate by the action of pulsating air pressure to which the diaphragm is subject.

One object of the invention is to provide a fluid pressure operated sound producer of the diaphragm type, in which the vibratory movement of the diaphragm is positive and certain.

Another object of the invention is to provide a sound producing device having chambers adapted to be supplied with fluid under pressure for causing a flexible sound producing member to vibrate, in which means are provided for limiting the vibration of the flexible member in both directions.

Another object of the invention is to provide a sound producing device which is simple and compact in construction and one which will be efficient for the purpose intended.

In the accompanying drawing, the single figure is a central sectional view of a sound producing device constructed in accordance with my invention.

As shown in the drawing, the device comprises a casing 1 having a chamber 2 and a central tube 4 that extends outwardly with a horn 5 mounted therein. Mounted to engage the annular face 6 of the tube is a flexible diaphragm 7 adapted to be held in position by a cap or cover 8.

According to my invention the cap or cover 8 is provided with a central cavity or chamber 9 which is adjacent to one side of the flexible diaphragm. A circular chamber 10 is provided in the inner face of the cap 8 and around the central chamber 9. A port 11 in the cap connects chamber 10 to the atmosphere. The numeral 12 indicates an annular shoulder adapted to be engaged by the flexible diaphragm on outward movement of same.

Secured to the central portion of the diaphragm 7 and extending into the open end of the tube 4 is a weight 13. A passage 14 in the casing 1 registers with a passage 15 in

the cap 8, said passage 15 opening into chamber 9 through a restricted port 16.

The chamber 2 is connected with a pipe 17, through a restricted port 18, whereby fluid under pressure is supplied to said chamber. 55

In operation, the fluid under pressure enters the horn through pipe 17 into chambers 2 and 9. The fluid under pressure in chamber 9 flows freely past the diaphragm stop in chamber 10 and out through atmospheric vent 11. The pressure in chamber 2 builds up slightly, forcing the diaphragm against its stop, thus permitting the pressure in chamber 2 to exhaust through vent tube 4, but tending to trap and permit the pressure to build up in chamber 9, said chamber being closed to atmospheric vent 11 by engagement of the diaphragm 7 with stop 12. Thus the diaphragm is forced back to its original position and is ready to repeat the cycle. In this way the diaphragm action is made positive in both directions instead of trusting to its perfection of material shape and location to return it correctly. 75

The vibration of diaphragm 7 produces a sound which amplified through the horn 5 and the addition of the weighted member 13 to the diaphragm 7 makes it necessary for the fluid pressure to build up to a higher point 80 before the diaphragm will move from engagement with the end of the vent tube 6, than would be the case with a weightless diaphragm, and when the diaphragm does move, the higher pressure causes a greater movement of said diaphragm and also a quicker return movement of same to effect a tighter engagement of the diaphragm with the tube 6. 85

While one illustrative embodiment of my invention has been described in detail, it is not my intention to limit its scope to that embodiment or otherwise than by the terms of the appended claims. 90

Having now described my invention, what I claim as new and desire to secure by Letters Patent, is:—

1. A sound producing device comprising a casing, a diaphragm mounted in said casing and subject to fluid pressure in chambers 100

at opposite sides of the diaphragm, and means for supplying fluid under pressure to said chambers.

2. A sound producing device comprising a casing, a diaphragm mounted in said casing and subject to fluid pressure in chambers at opposite sides of the diaphragm, fluid under pressure being supplied to one chamber through a restricted port and to the other chamber through another restricted port.

3. A sound producing device comprising a casing, a flexible diaphragm mounted in said casing, a fluid pressure chamber open to one side of the diaphragm, a fluid pressure chamber open to the other side of the diaphragm and to an atmospheric vent port, the movement of the diaphragm in one direction operating to restrict communication from the second chamber to the vent port.

4. A sound producing device comprising a casing, a flexible diaphragm mounted in said casing, a fluid pressure chamber open to one side of the diaphragm, the movement of the diaphragm in one direction operating to connect said chamber with the atmosphere, a fluid pressure chamber open to the opposite side of the diaphragm and to an atmospheric vent port, the movement of the diaphragm in one direction operating to restrict communication from the second chamber to said vent port.

5. A sound producing device comprising a casing, a diaphragm mounted in said casing and subject to fluid pressure in chambers at opposite sides of the diaphragm, means for supplying fluid under pressure to said chambers and the movement of said diaphragm alternately controlling the increase and decrease of the pressure of fluid acting on opposite sides of the diaphragm.

In testimony whereof I have hereunto set my hand, this 3rd day of February, 1930.

CECIL S. KELLEY.
